UNITED STATES PATENT OFFICE.

FRIEDRICH GUSTAV PABST, OF HAMBURG, GERMANY.

SHOE-LAST.

SPECIFICATION forming part of Letters Patent No. 600,678, dated March 15, 1898.

Application filed August 25, 1897. Serial No. 649,478. (No model.)

To all whom it may concern:

Be it known that I, FRIEDRICH GUSTAV PABST, a subject of the German Emperor, and a resident of Hamburg, in the German Empire, have invented certain new and useful Improvements in Shoe-Lasts, of which the following is a specification.

The present invention has for its object an improved shoe-last-like implement which is 10 designed to be placed inside a shoe in order to prevent changes or alterations of the form of the shoe resulting from the influences of heat and moisture, thereby securing and preserving the proper shape of the shoe.

15 The improved shoe last or tree mainly consists of a foot-shaped fore part, a heel-plate, and a connecting screw-spindle hinged to the heel-plate and engaging a suitable nut journaled in the said fore part. In consequence 20 of this construction and arrangement the last is capable of being adjusted in length in order to fit to shoes of different size. The insertion of the adjustable shoe-last into the shoe may easily be effected by hand by applying 25 only a moderate pressure. My improved implement is not to be confounded with the commonly-known shoe-stretchers, which are expandable lasts and serve for another purpose—viz., for expanding or distending a 30 somewhat tight shoe.

To make my said invention more clearly understood, reference may be had to the accompanying drawings, in which—

Figure 1 is a longitudinal vertical section 35 of the improved shoe-last; and Fig. 2, a detailed view, on enlarged scale, showing the nut and a part of the screw-spindle.

Similar letters refer to similar parts throughout both views.

40 The improved shoe-last is composed of the proper last part *a*, made of any suitable material and shaped according to form of the foot; of the heel-plate *d*, having the form of a shoe-horn and being provided with a handle 45 or ring *d'*, and of a threaded rod or screw-spindle *b*, connecting the heel-plate *d* with the fore part *a*. The rear end of the spindle *b* is hinged to the heel-plate *d* at *d*², while its threaded front end is screwed into a nut *c*, 50 Fig. 2. This nut *c* has lateral arms *c'*, carrying suitable trunnions *c*², with which the

said nut *c* is journaled in the side walls of the preferably trough-shaped last *a*, as clearly shown by Fig. 1. By this arrangement and connection of the parts the screw-spindle *b* 55 is not only capable of being turned in the nut *c* in either direction, but may also be moved or swung up and down, together with the heel-plate *d*, in a vertical plane, as shown by dotted lines in Fig. 1.

60 My improved shoe-last may be used in the following manner: After, by turning the screw-spindle *b*, the last or fore part *a* and the heel-plate *d* have been driven apart the proper distance, corresponding to the length 65 of the shoe to be operated, the last *a* is put into the shoe and then the heel-plate *d* pressed down into the shoe, so as to bring the heel-plate from the position shown by dotted lines 70 into the position shown by full lines, Fig. 1. By this down movement of the heel-plate, which acts and rests against the quarter of the shoe, the last *a* is pressed forward in order to cause the upper of the shoe to snug to the said last *a*, so that the shoe is not distended, 75 but only regains its proper shape and the appearance of a new shoe.

For facilitating the adjustment of the said improved shoe-last—that is to say, the regulation of its length—there is provided on a 80 flattened part *b'* of the screw-spindle *b* a scale which indicates the foot-lengths in shoe-measures, Fig. 2.

The hollow or trough-shaped recess of the last *a* must be of such form and dimensions 85 that for the purpose of ready and convenient storage and preservation and for conveyance the heel-plate and the spindle may be put into the said recess or trough of the last *a* by turning the nut *c* about its trunnions in the 90 proper direction, thereby bringing the whole implement into a compact shape.

Having fully described my invention, what I claim, and desire to secure by Letters Patent, is—

1. A tree for boots and shoes comprising a toe portion, a nut journaled in said toe portion a threaded rod engaging said nut, and a heel-plate hinged to the end of said rod, substantially as set forth.

2. A tree for boots and shoes comprising a shell-like toe portion, and a nut journaled in

said toe portion, in combination with a threaded rod adapted to engage the nut, and an adjusting-scale on one end and a heel-plate on the other end of said rod, substantially as described.

In testimony that I claim the foregoing as my invention I have signed my name, in pres-

ence of two witnesses, this 12th day of August, 1897.

FRIEDRICH GUSTAV PABST.
